UNITED STATES PATENT OFFICE

115,448

DESIGN FOR AN ELECTRIC FAN OR SIMILAR ARTICLE

Malcolm S. Park, Mount Kisco, N. Y., assignor to The Singer Manufacturing Company, Elizabeth, N. J., a corporation of New Jersey

Application January 5, 1939, Serial No. 82,160

Term of patent 14 years

To all whom it may concern:

Be it known that I, Malcolm S. Park, a citizen of the United States, residing at Mount Kisco, New York, have invented a new, original, and ornamental Design for an Electric Fan or Similar Article, of which the following is a specification, reference being had to the accompanying drawings, forming a part thereof.

Fig. 1 is a front view of an electric fan or similar article showing my new design.

Fig. 2 is a left side view of the article shown in Fig. 1.

Fig. 3 is a plan view of the same.

Fig. 4 is a perspective view of the supporting bracket which constitutes one element of the article illustrated in Figs. 1, 2 and 3.

I claim:

The ornamental design for an electric fan or similar article, as shown.

MALCOLM S. PARK.
